(57) **CLAIM**

The ornamental design for a mobile device screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a first image of a front view in a sequence for a mobile device screen or portion thereof with graphical user interface of our design;

FIG. 2 is a second image thereof;

FIG. 3 is a first image of a front view in another embodiment of the sequence for a mobile device screen or portion thereof with graphical user interface of our design; and,

FIG. 4 is a second image thereof.

The outermost sharp-cornered broken-line rectangle shows the perimeter of a mobile device screen. The broken lines outside this perimeter show portions of a mobile device. The dotted, dashed, and slashed broken lines within this perimeter show portions of the graphical user interface. The broken lines form no part of the claimed design.

The appearance of the transitional image sequentially transitions between the images shown in FIGS. 1-2 in a first embodiment, and FIGS. 3-4 in a second embodiment. The process or period in which one image transitions to another forms no part of the claimed design.
